UNITED STATES PATENT OFFICE.

GEORGE ANDREWS, OF BELLows FALLS, VERMONT, ASSIGNOR OF TWO-THIRDS TO AUGUST F. WINNEWISSEr AND WILLIAM E. CONWAY, OF SAME PLACE.

GUTTER ATTACHMENT.

SPECIFICATION forming part of Letters Patent No. 531,989, dated January 1, 1895.

Application filed March 28, 1894. Serial No. 505,492. (No model.)

To all whom it may concern:

Be it known that I, GEORGE ANDREWS, of Bellows Falls, in the county of Windham and State of Vermont, have invented certain new 5 and useful Improvements in Gutter Attachments, of which the following is a full, clear, and exact description.

My invention relates to improvements in that class of gutters and spouts which are connected with the eaves of a building to collect 10 and carry away the surplus water. A difficulty with such gutters and spouts is that snow and ice accumulates in them, thus damming up the water which freezes and causes 15 the gutter or spout to burst.

The object of my invention is to produce a simple attachment by means of which the gutter may be tipped up beneath the eaves and the spout also turned beneath the eaves 20 of a building, so that neither gutter nor spout collects any snow, ice, or other matter, and in case of rain the spout and gutter are turned back to position so that the water is carried away in a proper manner.

To these ends my invention consists of certain features of construction and combinations of parts, which will be hereinafter described and claimed.

Reference is to be had to the accompanying 30 drawings, forming a part of this specification, in which similar figures of reference indicate corresponding parts in all the views.

Figure 1 is a broken front elevation of a building provided with my improved attachments. Fig. 2 is a sectional plan on the line 35 2-2 of Fig. 1; and Fig. 3 is a broken side elevation of the building and the attachments embodying my invention.

The gutter 10 is of the ordinary kind and 40 is adapted to be supported beneath the eaves 11 of a building, the gutter resting in hangers 12 which are secured to the shaft 13 extending parallel with the eaves and journaled in bracket arms 14 which are secured to the 45 bracket plates 15, and these are fastened securely to the side of the building. Any suitable bracket may be used, however, for supporting the shaft. The shaft is provided, preferably at the end, with a crank 16 which 50 connects by a rod 17 with a crank 18 on the vertical shaft or rod 19, which is held in suit-

able supports 20 and is, at its lower end, provided with a crank handle 21 having a slot 22 therein adapted to receive a fastening stud 23 which is secured to the building and which 5 is adapted to form a support for the crank handle 21. At the opposite end of the gutter is an outlet 10^a delivering into the bent upper end 24^a of the spout 24 which slides vertically in its supports 25, these being secured to the building and it also slides in a support 26 which has cams 27 on its upper edge adapted to act on the cams on the lower edge of a collar 28, which loosely encircles the spout, has a handle 29 and is adapted to abut 65 with a collar 30 on the spout. It will thus be seen that by turning the handle 29 in one direction, the spout is raised and, by turning it in the other direction, the spout is lowered and when lowered its upper end may be turned 70 around beneath the eaves so that no water can run into it.

After the spout has been disengaged from the gutter, the handle 21 may be turned so as to rock the shafts 19 and 13 and the movement of the latter swings the hangers 12 inward and tilts the gutter beneath the eaves in the manner shown by dotted lines in Fig. 3, and thus the gutter is also kept clear of snow and ice. In case it rains, the spout may be 80 turned back and raised and the gutter may be also turned into a horizontal position ready to catch and carry away the rain which drops from the eaves.

Having thus fully described my invention, 85 I claim as new and desire to secure by Letters Patent—

1. The combination with the eaves trough having an outlet, of a vertically sliding rotary spout registering at its upper off-set end with 90 said outlet; whereby it may be lowered to disconnect it from said outlet and then turned to throw its upper end under the eaves, substantially as set forth.

2. The combination with the rocking eaves 95 trough having an outlet and an operating mechanism, of a vertically sliding rain spout registering at its upper end with said outlet and provided at its lower portion with mechanism for raising and lowering it to connect 100 and disconnect it and the said outlet, substantially as set forth.

3. A rain spout connecting at its upper end with the eaves trough, bearings in which said spout is free to slide and turn, a cam upper edge on one of said bearings, a collar turning 5 on the said spout and having a lower cam edge engaging the cam edge of the bearing and provided with an operating handle; the said spout having an annular shoulder on which the upper edge of the ring bears, substantially as set forth.

4. The combination, with the gutter and spout, of a manually operated cam mechanism for raising the spout into connection with said gutter and lowering it for disconnection therewith, substantially as described.

GEORGE ANDREWS.
